UNITED STATES PATENT OFFICE.

WILLIAM P. BUTLER, OF CHICAGO, ILLINOIS.

BLOW-PIPE LAMP.

SPECIFICATION forming part of Letters Patent No. 415,613, dated November 19, 1889.

Application filed June 8, 1889. Serial No. 313,582. (No model.)

To all whom it may concern:

Be it known that I, WILLIAM P. BUTLER, a citizen of the United States, residing at Chicago, in the county of Cook and State of Illinois, have invented new and useful Improvements in Blow-Pipe Lamps, of which the following is a specification.

This invention relates to that type of blow-pipe lamps used by tinners, plumbers, and printers, which comprise a portable gasoline tank or vessel having a rigidly-attached or stationary vapor-burner on its top wall and an air-pump mounted on the tank to compress or condense air for the purpose of forcing gasoline to the vaporizer of the burner.

The main object of my invention is to provide a novel blow-pipe lamp which can be practically and efficiently worked in an inverted position or upside down for a considerable time, which has been found very desirable in order to operate on objects or in places where the fixed burner on the top of an ordinary blow-pipe lamp could not otherwise be applied.

This invention also has for its object to provide a blow-pipe lamp of the type alluded to with novel means for preventing the gasoline and the vapor thereof from gaining access to the reciprocating plunger and the cylinder of the air-pump mounted on the tank.

These objects I accomplish by the features of construction and combination of devices hereinafter described and claimed, reference being made to the accompanying drawings, in which—

Figure 1 is a sectional side elevation of a blow-pipe lamp embodying my invention. Fig. 2 is a top plan view of the same, and Fig. 3 is a broken sectional view showing the lower end of the air-pump.

In order to enable those skilled in the art to make and use my invention, I will now describe the same in detail, referring to the drawings, wherein—

The numeral 1 indicates the portable gasoline tank or vessel having in its cover or top wall 2 an orifice closed by a screw-threaded or other plug or stopper 3, for supplying the tank with gasoline or other combustible liquid. The cover or top wall is also provided with a screw-threaded orifice 4, with which

engages the screw-nipple 5 of a horizontal tubular valve-casing 6, which projects laterally beyond the side wall of the tank, where it is provided with a pendent neck 7, secured to the upper end of an air-conducting tube 8. This tube extends down parallel with the tank, and its lower end is curved laterally and outwardly and connects with the valve-casing 9, screwed upon the lower end of the air-pump cylinder or barrel 10, which is provided near its upper end with an air-inlet orifice 11, and contains a packed plunger 12, secured to the lower end of the plunger-rod 13. The lower end wall of the pump-cylinder 10 is provided with a port in which works the guide-stem 14 of a downwardly-opening valve 15, which is adapted to be seated upwardly against the bottom wall of the cylinder to close the port through the medium of a cup-shaped cap 16, moved upward by a coiled or other spring 17. The communication between the air-tube 8 and the valve-casing 9 is constantly open; but the spring and valve close the valve-port each time the pump 13 is raised.

The air-valve casing 6 contains a rotary valve 18, having in one side a longitudinal groove 19, forming a port, which is parallel to the axis of the valve, so that when the latter is axially rotated to the position shown in Fig. 1 the groove communicates at one end with the nipple 5 and at the opposite end with the neck 7 for the passage of air into the tank above the surface of the gasoline therein contained. The air-pump cylinder is arranged in a vertical position at one side of the tank, and is supported on the latter through the medium of upper and lower rigid brackets or arms, so that the pump is sustained entirely independent of the air-tube 8.

To the cover or top of the tank is rigidly fixed, by a screw-threaded connection, the vapor-burner consisting of the perforated shell 20, packing-tube 21, needle-valve 22, and oil cup or receptacle 23 for starting the burner, as is ordinarily practiced in this type of lamp.

The packing-tube of the burner connects with a tubular neck 24, depending from the cover or top wall 2, and to this neck is secured a vertical secondary oil-reservoir 25,

open at its lower end to the interior of the tank by means of a supply-tube hereinafter described. This secondary reservoir is shown as composed of a tube of uniform diameter 5 and circular in cross-section, and at its upper end is in constant communication with the vaporizer of the burner. An oil conveying or supply tube 26 is arranged in the secondary reservoir and passes through a disk 27, 10 which is in contact with the internal surface of the reservoir, such supply-tube being of less diameter than the secondary reservoir, and rising up and within the latter, so that the combustible fluid flowing into the supply- 15 tube will overflow at its upper end into the secondary reservoir. The construction is such, as will be obvious, that even though the supply of fluid in the tank be exhausted the apparatus can still be inverted and worked with 20 the combustible fluid that has previously passed into the secondary reservoir, if occasion should demand. The object of this construction is to provide a supply of oil in the secondary reservoir below the burner that 25 will permit the lamp to be inverted or turned upside down, and then be practically used for a considerable length of time in such inverted position. By this means a lamp of the type specified having a stationary burner 30 fixed on the top or cover of the tank can be used in localities where the burner could not otherwise be applied.

Having thus described my invention, what I claim is—

35 1. In a blow-pipe lamp, the combination, with a portable oil-tank having the tube of a vapor-burner attached and rising from its top portion, and means for compressing air in the tank to force oil to the burner, of a 40 secondary oil-reservoir having its upper end connected with the tube of the burner at the top portion of the oil-tank, and an oil-supply tube rising within the secondary reservoir to fill the latter with oil from the tank for feeding the burner when the tank is inverted, 45 substantially as described.

2. In a blow-pipe lamp, the combination, with a portable oil-tank having a vapor-

burner attached to its top portion, of a secondary oil-reservoir suspended within the 50 tank from the cover or top wall thereof and connected at its upper end with the burner through the top portion of the tank, and a supply-tube for supplying the secondary reservoir, substantially as described. 55

3. In a blow-pipe lamp, the combination, with a portable oil-tank having a vapor- 60 burner, of a secondary oil-reservoir suspended within the tank and containing within it an oil-tube for conducting oil into the secondary reservoir and permitting the lamp to be operated in an inverted position, substantially as described.

4. In a blow-pipe lamp, the combination, with the oil-tank having a burner connected 65 with its top portion, of an air-pump having its cylinder arranged in a vertical position at one side of the tank and supported thereupon by upper and lower rigid brackets, an air-valve connected with the top of the tank, and an air- 70 tube leading from the valve-casing downward beside the tank and bent laterally and connected at its lower extremity to the pump, substantially as described.

5. In a blow-pipe lamp, the combination, 75 with an oil-tank having a burner connected with its top portion, of an air-pump having its cylinder arranged in a vertical position at one side of the tank and supported thereupon by upper and lower rigid brackets, a tubular 80 air-valve casing having a neck and provided with a nipple connected with the tank-cover, a rotary valve-plug having a longitudinal port for connecting at one end with the nipple and at the other end with the neck of the 85 casing, and an air-tube secured at its upper end to said neck of the casing and extending downward to and connected with the lower end of the air-pump, substantially as described. 90

In testimony whereof I have affixed my signature in presence of two witnesses.

WILLIAM P. BUTLER.
